UNITED STATES PATENT OFFICE.

BURTT J. HUBBARD, OF KOKOMO, INDIANA, ASSIGNOR TO AUTOMOTIVE ACCESSORIES, INC., OF KOKOMO, INDIANA.

WINDSHIELD-WING CONSTRUCTION.

Application filed January 27, 1922. Serial No. 532,134.

To all whom it may concern:

Be it known that I, BURTT J. HUBBARD, a citizen of the United States, and a resident of Kokomo, county of Howard, and 5 State of Indiana, have invented a certain new and useful Windshield-Wing Construction; and I do hereby declare that the following is a full, clear, and exact description thereof, reference being had to the accompanying drawings, in which like numerals 10 refer to like parts.

This invention relates to a wind shield wing construction, and the chief object thereof is to improve constructions which 15 have been heretofore employed such as that shown in my prior Patent No. 1,380,909 dated June 7, 1921.

The chief feature of the invention resides in the friction spring construction associated with the wing supporting rod and the mountings thereon in which it is movable. Such construction causes the relative movement between the rod and mountings to be 20 yieldingly and frictionally resisted, and also takes up any play that there may be between these members and prevents any rattle which there may be as a result of a bad fit or wear between the parts. Although 25 there may be a positive means for tightening the members against relative movement and locking them in adjusted position, it is awkward to adjust a wing of this nature upon loosening the locking means if it has entirely free movement. The proposed construction is adapted to retain the movable 30 parts in frictional contact, although they are entirely released by the locking means, so that adjustment thereof will be slightly resisted and they will be retained in the adjusted position by such frictional means until locked. It is the purpose of this invention to provide a simple construction for obtaining such frictional resistance and taking up play so as to prevent rattle.

40 The full nature of this invention will be understood from the accompanying drawings and the following description and claims.

In the drawings Fig. 1 is a side elevational view of a wind shield wing, the supporting means thereof and a support. Fig. 2 is an end elevational view of the wind shield wing and the supporting means, parts being shown in section. Fig. 3 is a transverse sectional view taken on the line 3-3 of Fig.

1 and in the direction of the arrows, and illustrates one form of support. Fig. 4 is a transverse sectional view taken on the line 4-4 of Fig. 1. Fig. 5 is an enlarged detailed view of one of the clamping members. Fig. 6 is a side elevational view of a wind shield, the supporting means thereof and a support. Fig. 7 is a transverse sectional view taken on the line 7-7 of Fig. 6. Fig. 8 is a transverse sectional view 65 taken on the line 8-8 of Fig. 6 and in the direction of the arrows and illustrates another and the preferred form of support. Fig. 9 is a plan view of the bracket means shown in Fig. 8. Fig. 10 is a side view of 70 a modified form of clamp.

In the drawings 10 indicates a supporting member such as the side bar or frame of a wind shield. 11 indicates a wind shield wing of transparent material, such as glass, and this wing may be of any desired shape. The wing is preferably apertured in a plurality of places, see Fig. 4. The apertures 12 thereof are provided with a bushing 13 of resilient or cushioning material such as 75 rubber. Upon the opposite sides of the wing and adjacent the aperture is a pair of washers 14 which are of similar material. A suitable ornamental nut 15 is associated with a unitary rectangular-shaped bracket 80 16 by means of the bolt 17. The bracket member 16 terminates in the bearing portion 17 and said bearing portion 17 is supported upon and secured to an elongated 85 hinge rod 18 by any suitable means or in 90 any suitable manner.

In the drawings there is illustrated two forms of supporting brackets, one of which is adapted to be fixedly secured to the supporting member 10 by being bolted thereto, and the other which is adapted to be adjustably and rigidly secured to said supporting member 10 by being clamped thereto. Both forms are illustrated in Figs. 3 and 95 4 respectively. In Fig. 1 the upper supporting portion having the elongated hinge rod 18 is the same as that shown in Fig. 3 and the upper portion of Fig. 2 and herein 100 said supporting bracket means comprises a socket portion 19 which is slotted at 20 and 105 in said slot is a spring member 21. The bearing portion 19 is provided with a threaded opening 22 to receive a bolt 23 which is adapted to rigidly secure another bracket member 24 having an opening for 110

the bolt 23. The bracket member 24 is provided with an elongated face 25 which is provided with a plurality of openings adapted to receive bolts 26 for rigidly securing the bracket 24 to the supporting member 10, see Fig. 3.

The other form of supporting clamp construction is illustrated in the lower portion of Figs. 1 and 2 and in Fig. 4 and comprises 10 a bearing portion 29 similar or identical with the bearing portion 19 and said bearing portion is likewise provided with a threaded opening 31 adapted to receive a clamping bolt 33 for securing a pair of complementary 15 bracket members 34, each having an inturned edge 35 abutting each other and a clamping portion 36 adapted to engage and support the member 10 and be rigidly secured thereto by means of the bolt 37 and nut 38.

20 Reference will now be had to Figs. 1, 2 and 5 wherein the means for associating the several supporting brackets and hinge rod and the means for locking the same together in the adjusted position is illustrated. It is, 25 of course, to be noted that while the invention has been described as containing a plurality of wing supported bracket means rigidly secured to the elongated hinge rod and said hinge rod being rotatably supported by the supporting bracket means described in the two preceding paragraphs, the construction may be reversed and such a reversal is contemplated as within the scope 30 of this invention.

35 Herein a plate portion 40 is rigidly secured to the elongated hinge rod 18 and in the present instance is shown integral with the wing supporting bracket 16. The plate 40 is provided with a flat face which is 40 knurled as shown in Fig. 5. A similar plate portion 42 is rotatably associated with the rod 18 and in the present invention is shown integral with the bearing or supporting bracket 29, see Fig. 2 and said plate portion 45 is substantially similar to that before described. Interposed between said plate portions and herein shown mounted on the rod 18 is a plurality of friction disks or washers 43. Any suitable number of friction disks may be used, but herein two are 50 illustrated for convenience. The lower and threaded end of the hinge rod 18 is slotted longitudinally at 44 and mounted upon said rod beneath the supporting member 29 is a lock washer 45 and another washer 46 having a tongue portion 47 seatable in the slot 44. An ornamental nut 48 having an enlarged hand engageable portion 49 is associated with the lower end of the rod 18 to 55 bear upon the non-rotatable washer 47 and thereby exert pressure upon the lock washer 45 and draw the plates 40 and 42 and washers 43 towards each other to frictionally lock the same together in adjusted position. A cotter pin 50 is associated with the

lower end of the rod 18 and prevents the loss of the nut 49. It is, of course, to be remembered that for convenience the plates 40 and 42 are shown integral and it will also be remembered that the locking construction may be duplicated. Herein the construction is shown associated with the lower bracket construction but it may be associated with the upper bracket construction, or it may be associated with both brackets.

75 In Figs. 5 to 9 inclusive the preferred form of the bracket means is illustrated, said bracket means being associated with a suitable supporting member 10 and the brackets 19 and 29 each in turn are associated with the rod 18 to support the wing 11 by means of the bracket 16. Herein the same numbers indicate identical parts and no further reference thereto will be made. In this modification of this particular bracket means, the 80 same is illustrated as comprised of a pair of identical bracket members which are secured together at two points and simultaneously secured to a supporting member 19 at one of said points. Both members are herein indicated generally by the numeral 60 and are drop forged. Each member comprises an offset supporting portion 61 which is provided with a longitudinal aperture 62 therein and surrounding said aperture is a depression 63 which is so formed that said wall of said aperture are depressed as indicated at 64. The body portion is extended at 65 to form a curved projecting member. The body portion is hollowed out to form side walls and said walls, as well as the projecting portion 65, are corrugated or serrated at 66 and it is the serrated portion 66 which is adapted to engage the rigid supporting member 10 heretofore described. The body 100 portion is provided with another aperture 68 which is depressed to provide a seat for the bolt 67 which secures the pair of members 60 together and to the support 19 by the threaded portion of said bolt 67 engaging the 105 threaded opening 31 of the member 19. The exterior surface adjacent the opening 68 and the surface of said opening or seat is serrated in order to provide a better gripping surface. Each of the members 60 is 110 provided with a projecting portion 70 and said projecting portion 70 cooperates with the walls of the other bracket member 60 to prevent lateral and longitudinal relative movement, said projections being positioned 115 at an angle. A suitable bolt 71 is positioned in the inclined aperture 62 and is receivable by a nut 72 also positioned in the inclined aperture 62 on the other bracket member.

120 In Fig. 10 is illustrated a modified form of clamp which is preferably formed by stamping the members from metal. Said clamp comprises a pair of complementary members which have the abutting portions 125 secured together by the usual bolt 133.

The clamps are provided with an off-set portion 132 and a body portion which is slotted at 164. The body portion terminates in a hook or engaging portion 136. Associated with the body portion and seatable in the slot therein is a bolt 137 and a nut 138. The operation of the same is substantially that heretofore described with reference to the clamp illustrated in Figs. 4 and 8.

10 The invention claimed is:

1. In a wind shield wing construction, the combination of a hinge rod member, a wing support mounted on said rod, a rod supporting member embracing said rod, and a bowed spring positioned between said rod supporting member and rod and extending longitudinally thereof for frictionally engaging the same for resisting relative movement between said rod and member.
- 15 2. In a wind shield wing construction, the combination of a hinge rod member, a wing

support mounted on said rod, a rod supporting member embracing said rod, and a spring positioned between said rod supporting member and rod so as to yieldingly bear 25 against the same for frictionally resisting relative movement between said rod and member.

3. In a wind shield wing construction, the combination of a hinge rod member, a wing 30 support mounted on said rod, a rod supporting member embracing said rod, one of said members having an internal recess on the inner surface thereof adjacent the other member, and a yielding spring mounted in 35 said recess in position to yieldingly engage the same for frictionally resisting the relative movement between said rod and member.

In witness whereof, I have hereunto af- 40 fixed my signature.

BURTT J. HUBBARD.
